UNITED STATES PATENT OFFICE.

WALTER H. COTTON, OF CHICAGO, ILLINOIS, ASSIGNOR TO UNION DRAFT GEAR COMPANY, OF CHICAGO, ILLINOIS, A CORPORATION OF DELAWARE.

DRAFT GEAR.

Application filed December 10, 1924. Serial No. 754,912.

This invention relates to draft gears for railway cars, and more particularly to draft gears of the friction type.

One of the objects of the invention is the provision of a draft gear having new and improved wedge releasing mechanism.

Another object of the invention is the provision of a draft gear having new and improved means for restoring the parts to normal position after compression.

Other objects of the invention are the provision of a new and improved draft gear that is easily assembled, cheap to manufacture, efficient in operation, and that is not likely to become broken, distorted or get out of order.

Other and further objects and advantages of the invention will appear from the following description taken in connection with the accompanying drawings, in which

Fig. 1 is a horizontal section of the device showing the same in operative position;

Fig. 2 is a section on line 2-2 of Fig. 1;

Fig. 3 is a plan view showing the device in collapsed position, with parts in section and parts broken away;

Fig. 4 is a perspective view of the follower sleeve;

Fig. 5 is a perspective view of the spring plate;

Fig. 6 is a perspective view of the wedge member; and

Fig. 7 is a perspective view of one of the friction plates, on a smaller scale.

On the drawings the reference 10 designates the center sills of a railway car, each of which is provided with a draft lug 11 and buffer lug 12, as is usual in such constructions. The draft gear which is mounted between these lugs comprises the two follower plates 13 which are adapted to engage the draft and buffer lugs in the usual manner. Mounted between the follower plates are a pair of sleeves 14 within which are mounted the friction elements for resisting the compression of said sleeves. These friction elements comprise one or more groups of plates which are adapted to frictionally engage each other and the inner sides of the sleeves. Preferably two groups, 15 and 16, of intercalated friction plates are employed, one at each side of the longitudinal axis of the gear, each group comprising the two sets of plates 17 and 18 overlapping at their inner ends.

Suitable means are provided for moving

the plates laterally against the sides of the sleeves in order to create friction to resist and absorb buffer stresses during the compression of the gear. In the form of the device selected to illustrate one embodiment of the invention, a pair of shoes 19 at each end of the gear in contact with the friction plates, is provided, which are adapted to be forced laterally by wedge blocks 20 having the inclined faces 21 at each side thereof for engaging the corresponding inclined faces 22 on said shoes. The outer ends of the wedge blocks 20 are adapted to extend beyond the sleeves 14 when the gear is in extended position. When the gear is collapsed, the follower plates 13 will force the wedges 20 inwardly, thereby causing the shoes to move outwardly against the friction plates and on further collapsing movement the follower plates 13 will engage the ends of the friction plates and the sleeves and collapse the same against the frictional resistance thereof.

Suitable means are provided for returning the parts to normal position after compression. It is desirable that the means employed for this purpose be so constructed that the wedge blocks will first be released and then the plates and sleeve will be moved outwardly to normal position. In the present construction the resilient means for releasing the wedge blocks is also employed to assist in returning the plates and sleeves to inoperative position. As shown on the drawing a resilient member such as the compression spring 23 is mounted between said wedge blocks to resist their movement toward each other. The wedge blocks may be provided with recesses 24 for receiving the ends of the spring and the parts may be and preferably are held in assembled relation by the rod or bolt 25. The wedge blocks 20 are provided with laterally extending lugs 26 which are adapted to engage retracting bars 27 mounted in notches 28 in the friction plates. The retracting bars 27 are mounted in the oppositely arranged notches 28, see Fig. 7, in the outer ends of the two sets of plates 17 and 18. The inner ends of the plates are reduced as at 29 so that they may pass between the retracting bars of the opposed plates during their compression. The parts are so arranged that the lugs 26 will not come into engagement with the retracting bars 27 until the wedge has been partially retracted. One of the wedge blocks 110

may temporarily stick, but if it does it will be released by the full force exerted by the spring when the outward movement of the opposite wedge is stopped by the engagement 5 of its lugs 26 with the corresponding retracting bars 27. By means of this arrangement the release of both wedge blocks is assured. This is considered an important feature of the invention.

10 A spring 31 is employed for yieldingly resisting the inward movement of the shoes 19 whereby the same will be forced laterally by the wedge blocks 20 during compression. Suitable means are provided for utilizing 15 this spring for returning the parts to normal position. As shown, this means comprises a spring seat or plate 32 at each end of the gear interposed between the ends of the spring 31 and shoulders 33 on the shoes 19 20 for moving the shoes outwardly after compression. These plates are also provided with lugs or projections 34 which are adapted to engage the retracting bars 27 at each side of the lugs 26 for moving the friction 25 plates outwardly.

The sleeves or sleeve followers 14 are also moved outwardly after compression by the retracting bars 27. A convenient manner of accomplishing this is shown on the drawings, 30 which consists in forming lugs 35 on the inner side walls of each sleeve adjacent its outer end. These lugs are adapted to be engaged by said bars and moved outwardly simultaneously with the friction plates.

35 The coupler butt 30 is provided with a stirrup or loop 36 for embracing the draft gear, as is usual in such constructions.

The operation of the device is as follows:

Upon the application of stresses of buff, 40 the forward follower 13 is moved inwardly, carrying with it the associated wedge block 20 against the resistance of the spring 23. The forward shoes 19—19 are wedged outwardly and advanced against the opposition 45 of the spring 31, thus forcing the rearward shoes 19—19 backwardly against the rearward wedge block 20 and causing their lateral movement. The friction plates are thus put under compression at both ends.

50 When the forward follower makes contact with the ends of the plates 18 and the sleeve 14, all of these elements are carried inwardly, the plates 17 and rearward sleeve 14 also moving inwardly, due to the high friction which has been developed, until they 55 make contact with the rearward follower 13.

The continued advance of the forward follower causes the plates 18 to move inwardly 60 against the frictional resistance of the parts with which they make contact, thereby, with the spring resistance, absorbing the compressing force. The limit of compressive movement is reached when the two sleeves make contact.

Upon release, the forward wedge block 65 20 and follower 13 are urged to their normal position by the spring 23. The lugs 26 which, in the initial compressive movement, will have been moved away from the retracting bars 27, again come into engagement 70 with them and move backwardly the plates 18. The backward movement of the wedge block 20 relieves the wedging action and the spring seats 32 are thereupon moved backwardly by the spring 31, their lugs 34 presently coming into engagement with the retracting bars 27, whereupon the two springs cooperate to restore the plates 18 and forward casing 14 to normal position. The bars 27 engage the lugs 35 to move the sleeves 80 outwardly.

As the spring 31 expands the wedging action at the inner end of the gear is relieved, but the friction plates remain under sufficient compression to insure the restoration 85 of the plates 17 and the inner sleeve 14 to normal position.

Under the influence of stresses of draft the same action takes place, the movement however being from the rearward end of the 90 gear, and upon the relief of these stresses the parts are similarly restored to normal position.

It is thought from the foregoing taken in connection with the accompanying drawings 95 that the construction and operation of my device will be apparent to those skilled in the art, and that various changes in size, shape proportion and details of construction may be made without departing from the 100 spirit and scope of the appended claims.

I claim as my invention:

1. A draft gear for railway cars comprising a group of intercalated plates, a friction shee at each end of said group slidale 105 along one of said plates, casings enclosing both end portions of the group of plates, resilient means for resisting the inward movement of said shoes, wedge members adapted to engage said shoes for forcing the 110 same laterally for compressing said plates, resilient means for resisting the inward movement of said members during the compression of said gear, and means whereby when the compression of said gear is released 115 the resilient means during initial movement will move said members and shoes outwardly independently and during final movement will cooperate in moving said plates outwardly.

2. In a draft gear, a pair of casings, a group of two sets of relatively movable intercalated friction plates within said casings, means for forcing said plates into frictional engagement during compression of said gear, 125 plate retracting bars for both sets of plates, a plurality of springs for resisting the inward movement of said means, and means

whereby said springs will actuate said bars successively for retracting said plates and said casings.

3. In a draft gear, a pair of casings, a plurality of sets of relatively movable intercalated friction plates within said casings, retracting bars associated with each set of plates, and a means including a plurality of springs for successively actuating said bars after compression of said gear for returning said plates to normal position, said bars engaging said casings on release of said gear for returning the same to released position.

4. A draft gear comprising a group of two sets of intercalated plates, means including friction shoes and a wedge element cooperating therewith at each end of said gear for forcing said plates laterally into frictional engagement with each other, means to limit the lateral movements of said plates, resilient means for resisting the inward movement of said wedge elements, retracting bars for each set of plates, and lugs on said wedge elements for engaging said bars during the outward movement only of said wedge elements, said bars being adapted to retract said casings during the release of said gear.

5. In a draft gear, a pair of groups of intercalated plates each comprising two sets of friction plates, a pair of shoes for engaging said plates at each end of said gear, a wedge member at each end of said gear for forcing said shoes inwardly and laterally against said plates, retracting bars connected to and movable with said plates, resilient means for resisting the inward movements of said wedge members, means on said members for engaging said bars during the outward movement only of said members, shoulders on said shoes, spring seats for engaging said shoulders, resilient means for engaging said seats for resisting the inward movements of said shoes, and means on said

seats for engaging said bars during the final 45 outward movement of said shoes.

6. In a draft gear, a pair of casings, a group of intercalated friction plates within said casings, means including shoes and wedges for creating transverse pressure on 50 said plates during compression of said gear, spring-pressed seat members for engaging said shoes, retracting bars interlocking with the plates, resilient means for engaging said seat members and wedges for causing the 55 same to act independently on said bars for retracting said plates after compression, and means on said casings for engaging said bars for retracting said casings upon release of the gear.

7. A draft gear, comprising members having frictional surfaces parallel with the axis of the gear, means including wedges for forcing said surfaces into frictional engagement during compression of said gear, 65 spring means for engaging said wedges, retracting elements, means on said members adapted to be engaged by said elements for retracting the same upon the release of the gear, and spring-pressed means for resisting 70 the inward movement of the shoes during compression of the gear and adapted to engage said shoes and said retracting elements on the release of the gear.

8. A draft gear comprising members having frictional surfaces, means including wedges and cooperating shoes for forcing said surfaces into frictional engagement, resilient means for resisting the inward movement of said shoes and wedges, 75 retracting bars positively engaging shoulders on the first-named members, and means associated with said shoes and wedges for successively engaging said bars for returning the parts to normal position after compression.

In testimony whereof I affix my signature.
WALTER H. COTTON.
